UNITED STATES PATENT OFFICE.

CHARLES B. VAN VORST AND NINA E. FULKERSON, OF LOS ANGELES, CALIFORNIA.

MATTRESS AND CUSHION.

1,138,264.

Specification of Letters Patent.

Patented May 4, 1915.

Application filed June 8, 1914. Serial No. 843,730.

To all whom it may concern:

Be it known that we, CHARLES B. VAN VORST and NINA E. FULKERSON, both citizens of the United States, residing at Los Angeles, in the county of Los Angeles and State of California, have jointly invented new and useful Improvements in Mattresses and Cushions, of which the following is a specification.

10 This invention relates to mattresses and cushions, and it has for its object to provide improvements in devices or structures of this kind with respect to maintenance of proper form and condition whereby the 15 length of life and comfort and satisfaction in use of such mattresses or cushions will be increased, due to increase of strength and resistance to wear and stress incident to service, and prevention of slipping or dis- 20 arrangement of the filler or body or stuffing portion or portions.

Numerous attempts have been made to provide mattress and cushion constructions which will produce the result above stated, 25 but all of them are open to numerous objections concerning expensiveness, want of positiveness and effectiveness in use or service, and general inefficiency.

The present invention has for its object to 30 provide improved mattress or cushion construction embodying or containing the above general required or desired features, which will be relatively simple and inexpensive in construction or formation, positive in operation, and durable in use and service, which will be slight in appearance, and which will be generally superior in efficiency and serviceability, rendering the mattress or cushion comfortable to the user and causing the 35 same to be maintained in proper usable shape or condition under long continued service.

With the above and other objects in view, the invention consists in the novel and use- 40 ful provision, formation, construction, combination, association and relative arrangement of parts, members and features, all as hereinafter described, shown in the drawing, and finally pointed out in claims.

50 In the drawing: Figure 1 is an isometric view of a mattress formed and constructed and organized in accordance with the invention; Fig. 2 is a detail transverse sectional view thereof, taken on the line x^2-x^2 , Fig. 1, and looking in the direction of the appended arrows; and, Fig. 3 is a bottom

plan view or inner face view of a portion of the top or bottom cover of the mattress shown in the other figures.

Corresponding parts in all the figures are 60 designated by the same reference characters.

Referring with particularity to the drawing, the improved mattress is shown therein as comprising top and bottom covers A and B respectively, between which extend side 65 or edge covers C, all of which are sewed together to form an inclosing case for the filler or body or stuffing D which as shown in the drawing may consist of layers d of felt or other material. All of the covers are pref- 70 erably formed of suitable textile material, although other flexible material may be employed. The side or edge covers C are of any preferred form and pattern, and the top and bottom covers may be of any par- 75 ticular shape or pattern desired, in accordance with the general design of the mattress or cushion. Each of the top and bottom covers A and B is provided with a plurality of spaced tufts E, usually arranged at 80 evenly spaced intervals, such tufts being connected together by cords or stitching, in the usual manner, the latter passed through the body or filler D.

In order to draw each of the covers A and 85 B down intimately upon or against or into the body D, in line extending between the tufts E, so as to produce a subdivided mattress or cushion formation, after the pattern pre-determined by the relative arrange- 90 ment and spacing of the tufts E, and to prevent shifting or slipping of the body or filler D within the casing consisting of the covers A, B, and C, we fold the material of such covers A and B, as at 4, forming plaits 95 extending between the tufts, such plaits, when the covers are in place, constraining the mattress-body from slipping, and producing a tight, permanent, satisfactory dis- 100 position and arrangement of the body or filler within the case. To maintain these plaited or folded formations 4, we provide lines of stitching 5 extending between the rows of tufts E, and intersecting the folds or plaits 4, preferably midway between 105 the respective pairs of tufts E, such lines of stitching 5 tacking together the folds or plaits at such intermediate points and preserving the formation of the same. Rein- 110 forcements F, preferably consisting of strips of tape or other inelastic material, are extended across the inner faces or surfaces

of the covers A and B, in line with the respective rows of stitching 5, the stitching being produced both through said strips of tape or the like F and the respective cover 5 A or B, longitudinally of the strips of tape.

The method of use and advantages of the invention will be understood from the foregoing description, taken in connection with the accompanying drawing and following 10 statement:—The strips of tape or other reinforcements F maintain the integrity of the rows or lines of stitching 5, and likewise prevent the material of the respective cover A or B from yielding in the directions 15 of the lines of stitching, thus preventing stretching of such material in the directions mentioned, and holding the plaits firmly, through the stitching and such strips, against opening up or becoming disarranged. The plaits or folds 4 produce lines 20 of depression in the respective cover, impinging upon and projecting into the material or body or filler D, effectively holding the same against shifting within the 25 case, and conserving the proper arrangement and distribution of the filler, in this manner insuring the best and most serviceable condition of the mattress or cushion with respect to both comfort of the user and 30 appearance. The plaits or folds 4 thus cooperate with the drawn together tufts E, to maintain the proper working or service condition and appearance of the mattress or cushion, and to conserve the life of the mattress and extend its period of satisfactory 35 service, so that the repair and making over of the mattress are thus rendered unnecessary.

Having thus disclosed our invention, we 40 claim and desire to secure by Letters Patent:

1. A mattress or the like having a cover, portions of which are folded to inwardly project, and lines of stitching extending transversely of such folded portions between 45 the ends thereof and maintaining the formation of the same.

2. A mattress or the like having a cover, portions of which are folded to inwardly project, and lines of stitching extending 50 transversely of such folded portions between the ends thereof and maintaining the formation of the same; reinforcements being provided for the cover and being co-extensive with the lines of stitching.

3. A mattress or the like having a cover, portions of which are folded to inwardly

project, and lines of stitching extending transversely of such folded portions and maintaining the formation of the same; said cover being provided with tufts between 60 which the cover folds extend, and said lines of stitching being arranged to intersect the folds intermediate of the tufts.

4. A mattress or the like having a cover, portions of which are folded to inwardly 65 project, and lines of stitching extending transversely of such folded portions and maintaining the formation of the same; said cover being provided with tufts between 70 which the cover folds extend, and said lines of stitching being arranged to intersect the folds intermediate of the tufts; reinforcements being provided for the cover and being co-extensive with the lines of stitching.

5. A mattress or the like, comprising a 75 case consisting of top and bottom covers and side or edge covers joined therewith, and a filler for the case; said top and bottom covers being provided each with tufts, means being provided uniting said tufts and 80 extending through said body or filler and depressing the tufts with respect to the body, each of said top and bottom covers being provided with inwardly projecting folds extending between the tufts and with 85 rows of stitching intersecting the folds at points between the tufts.

6. A mattress or the like, comprising a 90 case consisting of top and bottom covers and side or edge covers joined therewith, and a filler for the case; said top and bottom covers being provided each with tufts, means being provided uniting said tufts and 95 extending through said body or filler and depressing the tufts with respect to the body; each of said top and bottom covers being provided with inwardly projecting folds extending between the tufts and with 100 rows of stitching intersecting the folds at points between the tufts; inelastic reinforcements being provided for the cover and joined thereto by said rows of stitching and being co-extensive with said rows of stitching.

In testimony whereof, we have signed our 105 names to this specification in the presence of two subscribing witnesses.

CHARLES B. VAN VORST.
NINA E. FULKERSON.
